HAM PRESS

Clarence Butz, Muscatine, Iowa

Application September 19, 1944, Serial No. 554,804

4 Claims. (Cl. 100—57)

1

This invention relates to ham presses and is an improvement over the construction embodied in my prior patents, No. 1,792,411, dated February 10, 1931, and No. 1,935,015, dated November 14, 1933.

An object of this invention is to provide an improved ham press and method of pressing hams which will permit the more rapid pressing of the hams and will also permit the more rapid removal of the hams from the press.

In prior press constructions of this kind the ham is pressed into a mold or receptacle and it is a difficult matter to remove the ham from the mold without distorting the ham. In addition the use of a mold requires that the hams be of a predetermined average size for fitting into the mold. It is, therefore, another object of this invention to provide a ham press which will permit the pressing of hams of different sizes and which will facilitate the removal of the pressed ham from the press.

A further object of this invention is to provide an improved method of pressing the ham, which includes encompassing the ham in a bag and then inserting the encompassed ham in the press. By a method of this kind the ham will not become broken or split as it is being pressed due to the fact that the fabric of the covering will shape itself to the shape of the pressed ham, while at the same time providing a means whereby the pressed ham may be readily removed from the press without affecting the pressed shape of the ham.

A further object of this invention is to provide an improved press which is of simple construction so that it is readily portable and can be used at any desired location.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail side elevation of a ham press constructed according to an embodiment of this invention.

Figure 2 is a sectional view taken substantially on the line 2—2 of Figure 1.

Figure 3 is a sectional view taken on the line 3—3 of Figure 2.

Figure 4 is a sectional view taken substantially on the line 4—4 of Figure 2.

Figure 5 is a fragmentary sectional view taken on the line 5—5 of Figure 2.

Figure 6 is a detail side elevation partly broken away of the pressure means for applying pressure to the ham.

2

Figure 7 is a plan view of the latch retracting spring.

Figure 8 is a fragmentary side elevation of the press frame construction.

Referring to the drawings, the numeral 10 designates generally a base which is of rectangular configuration and which has rising from the opposite ends thereof a pair of uprights 11 and 12. The uprights 11 and 12 are secured together at their upper ends by a connecting bar 13. The upright 11 is braced by means of a pair of upwardly convergent bracing members 14 and 15 and upright 12 is braced by means of upwardly convergent bracing members 16 and 17. A press construction, generally designated as 18, is mounted within the frame structure hereinbefore described, and includes a base plate 19, which rests on base 10 between the uprights 11 and 12. Base 19 has secured to the opposite ends thereof a pair of upwardly extending members 20 and 21, which are braced in an upright position by bracing members 22 and 23, respectively. Upright 20 is formed with a plurality of elongated slots 24, and upright 21 is formed with complementary elongated slots 25. The slots 24 and 25 constitute keepers for the latches to be herein-after described.

A pressure plate 26 is vertically slidable between the uprights 20 and 21 and is formed at the opposite ends thereof with guide lugs 27 and 28. There are two lugs 27 engaging on the opposite vertical edges of upright 20 and there are two lugs 28 engaging on the opposite vertical edge of upright 21. A second plate 29 is disposed above pressure plate 26 and is formed adjacent the opposite ends thereof with openings 30 and 31 within which the uprights 20 and 21 loosely engage. An angle member 32 is fixed to plate 29 at the lower side thereof and constitutes a guide for engagement of the outer side of upright 20. A second angle member 33 is also fixed to the lower side of plate 29 and slidably engages on the outer side of upright 21.

Plate 29, as shown in Figures 3 and 4, is formed at the opposite ends thereof with outwardly opening slots 34 and 35 within which vertically disposed guides 36 and 37 fixed to the inner sides of uprights 11 and 12, respectively, are adapted to loosely engage. In this manner the base frame construction will guide second pressure plate 29 and this plate will also be guided by uprights 20 and 21. A ham pressing spring 38 is interposed between plates 26 and 29, and is secured at its lower end to plate 26 by means of a disc shaped block 39 which is secured to plate 26 by fastening members 40. Block 39 is formed in the lower side thereof with a recess 41 within which the terminal end 42 of spring 38 is adapted to be clamped. An upper block 43 is secured to the lower side of plate 29 by fastening members 44 and block 43 is formed with a recess 45 within

which the upper terminal end 46 of spring 38 is adapted to be clamped.

Plate 29 is adapted to be moved downwardly by means of a pressure bar 47, which has secured to the lower side thereof a block 48 formed with a recess 49 within which plate 29 is adapted to be received, and block 48 is also formed with a central cutout 50 within which the latch retracting spring to be hereinafter described, is adapted to loosely engage. The recess 49 forms a pair of downwardly extending lugs 51 at the opposite lengthwise edges of plate 29, so that pressure bar 47 cannot shift transversely with respect to plate 29. Bar 47 with block 48 is not connected to plate 29, being removable from this plate after plate 29 has been moved downwardly and spring 38 placed under the desired tension.

In order to provide a means whereby plate 29 may be latched in ham pressing position, I have provided a pair of latches 52 and 53 which are slidably carried by the plate 29 inwardly of the uprights 20 and 21. Latch 52 is slidably mounted in a housing 54 and is spring pressed to a latched position by means of a spring 55.

A headed pin 56 is fixed to latch member or bolt 52 and slidably extends upwardly through a slot 57 formed in plate 29. Latch member 53 is slidably mounted in a housing 58 and is urged to a latching position by means of a spring 59. An upwardly extending headed pin 60 is carried by the latch or bolt member 53 and slidably extends through a slot 61 formed in plate 29. As plate 29 is moved downwardly under pressure from bar 47 latch members 52 and 53 will engage in selected ones of slots or keepers 24 and 25. At the same time plate 29 is moved downwardly, plate 26 will be moved downwardly under the tension of spring 38 and thereby place a boned ham 62, which is encompassed by a fabric bag 63, under the desired pressure.

When it is desired to release spring tensioning plate 29 a latch releasing spring 64, which is formed with loops 65 and 66 at the opposite ends thereof, is engaged with pins 56 and 60. Spring 64 when stretched between pins 56 and 60 is of greater tension than springs 55 and 59 so that a slight downward movement of plate 29 with spring 64 engaged with latch pins 56 and 60 will pull latches 52 and 53 inwardly to released position.

In the use and operation of this press, plate 29 is initially in its unlatched position as shown in Figure 1. The encased ham is placed on base member 19 and the latter is placed on lower base 10 of the frame structure. The bag is tied, as indicated at 67, and it will be understood that initially the ham 62 is boned so that it may be shaped in the desired configuration. Pressure bar 47 has block 48 engaged with plate 29 and pressure in a downward direction is applied to bar 47. This pressure may be the weight of an operator who has his hands gripped to bar 47 on opposite sides of uprights 11 and 12. Plate 29 is moved downwardly along guides 36 and 37 and when in a lower position will engage guides 20 and 21. Plate 29 is moved downwardly to tension spring 38 and the latter applies the tension to pressure plate 26 which engages the encased ham. As plate 29 moves downwardly along uprights 20 and 21 latch members 52 and 53 will engage in successive keepers 24 and 25.

It is desirable that the ham be left in the press for a short period of time so that it will retain its pressed shape. The press embodying base 19, uprights 20 and 21 and plates 26 and 29 may be

removed as a unit from the base plate by lifting the entire unit upwardly along guides 36 and 37. After the ham has assumed its desired shape, spring 64 is applied which has loops 65 and 66 engageable with pins 56 and 60, respectively, and plate 29 may then be moved downwardly a short distance whereupon spring 64 will move latch members 52 and 53 inwardly to released position.

By providing a press as hereinbefore described and included, by the improved method of pressing the ham which embodies the encasing of the ham in a heavy fabric bag, the pressed ham may be more readily removed from the press without any portion of the ham sticking to the press, and if desired the pressed ham, with the bag, may be placed in a refrigerator to cool to the desired degree and, subsequently, the bag 63 may be removed from the ham.

What I claim is:

1. A ham press comprising a frame including a base, uprights arising from said base, guides carried by said uprights, a lower plate seated on said base, a pair of uprights fixed to said plate and formed with complementary keepers, an upper plate slidably engaging said guides and formed with openings through which said second uprights are adapted to pass, spring-pressed bolts carried by said upper plate engageable with selected keepers an intermediate plate slidably between said second uprights, a spring interposed between said upper and intermediate plates, and means for moving said upper plate downwardly to thereby tension said spring and place said intermediate plate under predetermined pressure for pressing a ham disposed between said intermediate and lower plates.

2. A ham press as set forth in claim 1 including a pair of pins carried by said bolts, and a removable bolt releasing spring connected between said pins.

3. A ham press comprising a base, a pair of uprights rising from said base, opposed vertical guides carried by said uprights, a press unit removably engaging on said base between said uprights, said unit comprising a lower plate, a pair of uprights carried by said lower plate, each of said second pair of uprights including vertically spaced apart keepers, an intermediate presser plate slidably between said second pair of uprights, an upper presser plate slidably engaging said guides and formed with openings through which said second pair of uprights loosely engage, spring-pressed bolts carried by said upper plate engageable with selected keepers upon downward movement of said upper plate, a tensionable spring secured to and between said intermediate and upper plates, and means for forcibly moving said upper plate downwardly.

4. A ham press as set forth in claim 3 including removable spring means for automatically moving said bolts to released position.

CLARENCE BUTZ.
